UNITED STATES PATENT OFFICE

RUSSELL C. GREENLEES, OF GLADSTONE, MICHIGAN

CLOSURE FOR COLLAPSIBLE TUBES

Application filed December 11, 1931. Serial No. 580,424.

This invention relates to a novel contribution to that class of inventions generally referred to as collapsible tubes and commercially used for containing and dispensing chemical, medicinal and pharmaceutical preparations, such as toothpaste, shaving cream, ointment and the like.

The principal novelty is, however, predicated upon the development of a new type of closure having the faculty of movement to an open position under the action of pressure from the contents of the tube, and automatically returnable to a closing position by simple spring means when the pressure is released.

Having in mind the desirable attributes of simplicity, economy and efficiency, I have evolved and produced a practical closure susceptible of accomplishing the aforesaid results in a manner calculated to fulfill the requirements of an invention of this class.

Other features, advantages, and objects will become more readily apparent from the following description and the accompanying drawings.

In the drawings:

Figure 1 is an elevational view of a collapsible tube equipped with the improved closure.

Figure 2 is a fragmentary view of the upper portion of the tube observing the discharge orifice of the closing cap.

Figure 3 is an exaggerated view in section and elevation utilized to disclose the details in a magnified manner.

Figure 4 is a view like Figure 3 showing the closing cap occupying its open position.

Figures 5, 6, and 7 are detail views of the cap per se.

Figure 8 is a perspective view of the return and maintenance spring for the cap.

Figure 9 is a view like Figure 3 showing a different type spring used.

By way of introduction, I would point out that the only difference between the type of structure illustrated in Figure 3, as contrasted with Figure 9 is the spring construction. Otherwise the details are the same, and like reference characters will be employed throughout all views of the drawings.

Referring now to the drawings in detail, the receptacle or body portion of the tube is denoted by the numeral 10, the tube being provided at its bottom with the usual clenched fastener 11. As seen in Figures 3, 4, and 9, the upper open end portion of the tube is thickened somewhat as denoted at 12, and internally screw-threaded as indicated at 13. This arrangement is provided to permit the rim portion 14 of the lid 15 to be threaded or tapped into place after the tube is filled.

The lid 15 is of dome-like configuration as is customary and is provided with a discharge neck 16 through which the contents of the tube are ejected under pressure in the customary manner by rolling the lower end portion of the tube.

The closure, as a unit, is generally designated by the numeral 17 and comprises a cap constructed to fit over the discharge neck. The cap includes a closing disc 18 and a segmental flange 19 fitting telescopically down over the complementary portion of the neck. This arrangement provides a discharge opening or orifice 20 on one peripheral side of the cap allowing the contents to be squeezed out when the cap is in the open position represented in Figure 4.

Attached to and depending centrally from the disc 18 is an operating rod 21 having an eye 22 at its lower end, said eye fitting into keeper notches 23 formed in the central portion of the longitudinally bowed flat spring 24. This spring has its opposite ends bent or curled as indicated at 25 to permit it to be confined in the rim portion of the lid 20 as illustrated in Figures 3 and 4.

It will be observed that these bent ends 25 function as shoes and are maintained in moving contact with the underside of the lid so as to permit the spring to function properly. Normally the spring is bowed downwardly as seen in Figure 3 to hold the cap closed, but is straightened out and allows the cap to open when pressure is exerted against the disc 18.

It is obvious that the pressure is built up against said disc 18 when the tube 10 is rolled in the customary manner for forcibly ejecting the contents from the neck 16. Just as soon as the pressure is relieved the spring

24 comes into play to reseat the disc 18 and thereby close the cap.

As before implied, the only difference in the modification illustrated in Figure 9 is that a coiled spring 26 is substituted for the flat spring. The convolutions of this spring are such as not to interfere with the free discharge of the contents of the tube. Possibly this arrangement is less expensive than the flat spring arrangement and has less tendency to obstruct the discharge of the contents of the tube.

In developing this invention, I have discovered the need for simple and economical automatically operable closures for collapsible tubes, and it is believed that the form and arrangement herein disclosed and described will fulfill the requirements of a structure of this class in a dependable and satisfactory manner. Not only this, there is less likelihood of losing the closing cap because of the fact that it is permanently attached to the cover or lid.

In addition, the idea of making the cover and closing cap and associated details in the form of a single unit for application after the tube is filled constitutes an important and distinguishing feature of the invention.

It is thought from the foregoing description that the advantages and novel features of the invention will be readily apparent.

It is to be understood that changes may be made in the construction and in the combination and arrangement of the several parts provided that such changes fall within the scope of the appended claims.

I claim:

1. In a structure of the class described, a collapsible tube having one end thickened and internally screw-threaded, a dome-like cover having a screw-threaded rim threaded into the tube, further having a central upstanding discharge neck, a cap for said neck, said cap including a closing disc and a segmental rim fitting telescopically around the neck and forming a discharge opening, a rod attached to and depending from the central portion of the disc and depending through said neck into the interior of the tube, and spring means to which the inner end of said rod is connected, said spring means being nested in the rim of said cover.

2. In a structure of the class described, a collapsible tube provided with a discharge neck, a closing cap for said neck, said cap including a closure disc and a segmental ring fitting telescopically around the neck, a rod attached to the disc and extending into the tube through the neck, and spring retaining means and automatic closing means attached to the inner end of the rod and confined within the tube.

In testimony whereof I affix my signature.
RUSSELL C. GREENLEES.
